HIGH-TENSION MAGNETO IGNITION APPARATUS FOR INTERNAL-COMBUSTION ENGINES.

1,016,895.

Specification of Letters Patent.

Patented Feb. 6, 1912.

Application filed April 6, 1909. Serial No. 488,278.

To all whom it may concern:

Be it known that I, ALEXANDER MARCUS PATTON, a subject of the King of Great Britain and Ireland, and residing at Cuba 5 street, Belfast, Ireland, have invented certain new and useful Improvements Connected with High-Tension Magneto Ignition Apparatus for Internal-Combustion Engines, of which the following is a specification.

This invention relates to the kind of driving connection between an internal combustion engine and its magneto igniter, wherein a spring, arranged between the 15 driving part of the motor and the armature shaft, is put under tension during the period that the latter is held stationary by a pawl mechanism, and is relaxed causing the armature to rotate rapidly and generate an intensive spark, after the pawl mechanism has been released, preferably by centrifugally acting devices, the pawl remaining 20 inoperative while the motor rotates at high speed.

The object of the invention is to provide a simplified construction which is at the same time very efficient.

The present invention consists in an improved driving connection of the kind referred to, wherein the ends of the spring are secured to the armature and driving shafts respectively, and the release of the pawl for the purpose of starting the rotation of the motor is effected by a lever 35 which connects one end of the said spring to the driving shaft.

The invention also consists in providing a pawl or pawls, depending from the armature shaft inside a ratchet secured to the 40 stationary part of the magneto.

The invention further consists in the improved driving connections between an internal combustion engine and its magneto igniter hereinafter described with reference 45 to the accompanying drawing, in which,

Figure 1 is a side elevation partly in section, illustrating one form of connection according to the invention; Fig. 2 being a cross section illustrating a ratchet and pawl 50 in detail; Fig. 3 a front elevation, and Fig. 4 a sectional plan corresponding to Fig. 1.

In carrying out the invention according to one mode a hollow ratchet, *a*, having a number of ratchet slots, *b*, according to the

number of firing points per revolution is 55 secured to any convenient stationary part of the frame of the magneto machine, *c*. A sleeve, *d*, is mounted upon the armature shaft, *e*, and carries a pawl, *f*, adapted to engage in one or other of the slots, *b*, under 60 the action of a spring, *g*, when the shaft, *e*, is being slowly rotated. The engine shaft or other driving shaft, *h*, is provided with two arms, *i*, to which springs, *k*, are attached, the latter being also secured to the 65 sleeve, *d*, for instance by means of hooks, *l*. When the engine shaft, *h*, is stationary and also under normal running conditions the arms, *i*, are in contact with projections or stops, *m*, upon the sleeve, *d*, but when the 70 shaft, *h*, is slowly rotated, as for instance when the engine is being started by hand, the arms, *i*, move away from the stops, *m*, and tension the springs, *k*, until one of the arms, *i*, strikes a balance weight, *n*, keyed 75 to a pin (*r*) formed integral with the pawl *f*, and disengages the latter from its respective slot, *b*, in the ratchet, *a*. The ratchet is thereupon released and rapidly rotates under the action of the springs, *k*, 80 so that a rapid rotation is imparted to the armature shaft, *e*. If the engine shaft, *h*, then rotates at a high rate the centrifugal force acting upon the weight, *n*, will cause the latter to overcome the action of the 85 small spring, *g*, and the pawl, *f*, will be able to overrun the ratchet, *a*, so that the sleeve, *d*, can be directly driven through the arms, *i*, and springs, *k*.

In Fig. 3 the positions of the parts when the pawl, *f*, is in engagement are indicated in full lines whereas the dotted lines indicate the positions at the moment of release. The releasing arm, *i*, may be so arranged that it will move forward away from the 95 projection, *m*, through an angle of about 45° before it strikes the balance weight, *n*, and releases the pawl, *f*.

The operation of this mechanism is as follows:—The magneto machine being timed 100 in the ordinary way so that the spark occurs at the completion of the compression stroke of the engine, the ratchet, *a*, is so set that the pawl *f*, engages with it about 45° before this point. As soon as the pawl, *f*, 105 engages the ratchet, *a*, the armature and spindle, *e*, are locked, whereupon the driving shaft, *h*, revolving with the engine, the arms,

i, leave the stops, *m*, and tension the springs, *k*. The driving shaft, *h*, with its arms, *i*, must be set to engage the balance weight, *n*, connected with the pawl, *f*, so as to throw it out of engagement when the engine reaches the top of the compression stroke. When the pawl, *f*, is released the armature is free to move forward under the action of the springs, *k*, the latter at once bringing the stops, *m*, into engagement with the arms, *i*. From the original setting of the magneto it will be seen that at the end of the movement of the armature the primary circuit must be ruptured before or at the moment that the stops, *m*, come in contact with the arms, *i*, and owing to the rapidity of the movement a good spark is insured. It will be also noticed that should the spark controlling lever on the magneto (not shown) be set so that normally the rupture of the primary circuit occurs earlier when the lever is advanced, it cannot occur until the engine reaches the top of the compression stroke, since the armature cannot move until the pawl, *f*, is thrown out of engagement with the ratchet, *a*, this having been set to occur at the top of the compression stroke. It follows that it is possible where desirable to work with fixed ignition without controlling levers of any kind. It is not necessary to set the magneto slightly advanced, this being retarded by the mechanism for starting purposes. When the spark has occurred and the speed of the engine begins to in-

crease, the pawl, *f*, has insufficient time to fall into the slot, *b*, on the ratchet, *a*, and it is carried over by its own inertia, and as it is slightly cut away on its face in order to overcome the wear that would result from the constant jumping of the pawl as it passes over the slot the before mentioned balance weight, *n*, is provided which under the influence of the centrifugal force overcomes the spring, *g*, and holds the pawl, *f*, out of engagement. 45

I claim:

A driving connection of the type referred to comprising in combination a driving shaft, a driven shaft, a lever upon the driving shaft, a sleeve mounted upon the driven shaft, a spring having one end connected with the driving shaft and the other end connected with said sleeve, a stationary hollow ratchet, a pawl within said ratchet and pivoted upon the aforesaid sleeve, a weight connected with said pawl and adapted to be engaged with the aforesaid lever on the driving shaft for the purpose of releasing the pawl from the ratchet and a stop upon the sleeve for engaging said lever, substantially as and for the purpose hereinbefore set forth. 60

In testimony whereof, I affix my signature in presence of two witnesses.

ALEXANDER MARCUS PATTON.
